UNITED STATES PATENT OFFICE.

MAX MAURAN, OF NIAGARA FALLS, NEW YORK, ASSIGNOR TO THE MATHIESON
ALKALI WORKS, INC., OF NEW YORK, N. Y., A CORPORATION OF VIRGINIA.

MULTIUNIT TANK CAR.

Application filed June 24, 1924. Serial No. 722,042.

This invention relates to improvements in multiple unit tank cars for the transportation of liquefied gases.

In the transportation of liquefied gases such as liquefied chlorine, liquefied sulphur dioxide, etc., it has been necessary heretofore to ship the liquefied gases in relatively small containers, of one ton capacity or less, especially designed and constructed for withstanding the high pressures of the liquefied gases contained therein. The shipment of the liquefied gases in this way involves an excessive cost for the containers and for freight charges in their transportation since the containers must be returned empty. The amount of the liquefied gases which can be transported in such a container, moreover, is limited, for only about fifteen one-ton containers can be directly secured on a car of usual size, so that the load is only fifteen tons of liquefied gas, or one-half the normal load of a tank car.

Tank cars which have a single large tank are unsatisfactory for transporting liquefied gases. It is difficult to prevent injury or weakening of the tanks, especially by corrosion when corrosive gases are transported and where it is necessary to insulate the tanks to prevent them from overheating during transportation. Also the transportation of such gases in a car having a single tank presents a potential risk of a major order in case of accident to the car.

Since tank cars employed for the purpose of transporting liquefied gases are ordinarily so constructed as to be adapted simply for this one purpose, it is desirable that the car be used to its utmost capacity since the tanks must be returned empty and consequently one stage of the journey is unprofitable.

The present invention, therefore, is directed to the provision of a multi-tank car which permits the transportation of liquefied gases in large containers, these containers being of such a size as to make possible the transportation of greater quantities of the liquefied material than has been heretofore possible. Also the car constructed according to the present invention permits of the shipment of the material with equal safety although the tanks are of greater size than heretofore used, and this car affords numerous further advantages by reason of the facility with which the material may be

withdrawn from the tanks either in the liquid or gaseous form.

The car of the present invention involves the use of a relatively small number of tanks, each of which contains a considerable quantity of the liquefied gases. These tanks are constructed so as to withstand safely the pressures involved and are firmly and securely mounted on the car so as to form a substantially integral part thereof, being capable, however, of removal therefrom should occasion arise.

In transporting such materials confined under heavy pressure in tanks, it is important, especially when the liquid is of a highly noxious and destructive character, not only to insure that the tanks are held securely in place, but these tanks should be designed so that they do not have a considerable longitudinal dimension so as to prevent the end thrust or water hammer effect which is of great importance and may result in damage in the case of a long car by reason of the tendency of the liquid to pile up at one end or the other whenever the motion of the car is suddenly started or stopped. The multi-tank car of the present invention is constructed to minimize this effect and to prevent injury to the tanks while the car is in transit, due to strains to which the mooring of the tanks is subjected.

According to the present invention the car structure is especially strengthened at those points where the greatest strains are placed and the tanks are designed so that a quantity of the gases having a weight at least equal to the minimum car load tonnage may be transported. By this construction, therefore, the capacity of the car is utilized to the best advantage and it follows that the transporting of the gases is much less expensive than was previously the case since the car is fully loaded in one stage of the journey. Furthermore, the individual tanks are so designed that their contents may be removed either in the gaseous or liquid form and the connections are such that the several tanks may be emptied simultaneously, or else the contents may be withdrawn from one tank at a time. Various other advantages incidental to the construction now to be described will be apparent from the following more detailed construction.

The construction of the car which I now

consider preferable involves the use of a main structural element comprising a central box girder which runs lengthwise of the car body and is supported on trucks at either end. The car preferably is of sufficient size to carry four tanks, each of which contains about seven and one-half tons of liquid chlorine. These tanks are generally cylindrical in form, having domed ends, and are arranged with their axes lying lengthwise of the car. Extending from either face of the central girder are supporting members forming cross beams, and these cross beams are arranged in pairs so that each tank lies over and is supported by two cross beams. The tanks rest on cradle members which are suitably secured to the cross beams and each cradle member extends entirely beneath the tank so that the tank resting on the cradle member is supported in part by the central girder and the cross beams. The cradle members are also provided with suitable strap members which encircle the container and hold it in place on the cradle. Mounted on the central girder, between each pair of tanks, and also at the outer end of each end tank, are small cradle members in the form of blocks which serve to prevent the longitudinal movement of the tanks and also provide a support for them. With this arrangement the tanks are held in place securely and the weight of each tank, which, when full, is quite great, is so taken up by the car framework that the stresses are evenly distributed and no part of the car structure is subjected to undue strains.

If desired, the car may be floored over and insulating material supported by the floor may be used to enclose the tanks. The cradle members on which the tanks are supported are so arranged that the tanks are supported clear of the floor level so that the insulation may extend completely around the tanks. The purpose of the installation is to introduce a time factor so that in case the tanks are subjected to excessive heat a considerable interval will elapse before the temperature of the liquefied gases rises to a point where undue strains are placed on the tank body. The mass of insulation which may be used to encase all of the tanks mounted on the car, may, in turn, be encased within a sheathing of suitable material, and running boards may be mounted along the ends of the cross beams and also along the sheathing near the top of the tanks. The tanks are provided with the usual valved draw-off connections at the top, and the running boards permit easy access to these valves. Also, draw-off connections may be provided so that the contents of the tanks may be discharged either in the gaseous or liquid form, and these draw-off connections may be connected to mains extending throughout the length of the car so that

the several tanks may be discharged through a single connection.

It will be seen that with the construction thus briefly described, the tonnage capacity of the car is utilized to the best advantage, since the total weight of material which may be transported in these large tanks approximates the actual tonnage capacity of the car and is much greater than the tonnage which can be carried in small containers, such as have heretofore been used. The tanks are mounted individually in place and rest on their cradle members with a slight wedging action, so that the tanks are firmly held in position and no securing devices are required which pass through the tank shell. This is a matter of great importance in the case of tanks which contain large quantities of liquid and which are subjected to considerable strains during transportation, owing to the movement of the liquid. Also, the tanks which are employed in the new car may be readily kept clean, which is important when liquids of a corrosive character are being transported. The tanks, while designed primarily for the shipment of material such as liquefied chlorine, which is transported at a pressure of from 75 to 100 pounds per square inch, may also be used for other liquefied gases, such as liquefied sulphur dioxide. Also, this car is advantageously used in the transportation of gasoline, and particularly of casing head gas, which contains large quantities of light and readily volatile constituents which must be maintained under a substantial pressure during transportation.

In the accompanying drawings there is illustrated that construction of the multi-tank car of the present invention which is now considered most advantageous, and in these drawings,

Fig. 1 represents a side elevation of the car with parts in section,

Fig. 2 is a top plan view of the car showing one tank in section taken substantially on the line 2-2 of Fig. 1, and

Fig. 3 is a transverse vertical cross-section through one of the tanks and the car body.

Referring now to these drawings, the car is shown as having a central box girder 4 which extends throughout the length of the car. This girder is built up of plates and angle members in any convenient way so as to have the necessary strength and rigidity and it has a greater depth at the middle than at either end, as shown in Fig. 1. At the ends it rests on trucks, (not illustrated, but the position of which is generally indicated by the wheels shown diagrammatically at 5.) The car here illustrated is designed to carry four tanks which are placed end to end throughout its length, and in order to support these tanks the central girder is provided with a plurality of cross beams 6.

Each cross beam is built up of plates and angle members so as to have the necessary strength and rigidity and each cross beam is in two parts so that the complete beam 5 extends from one edge of the car to the other. Extending longitudinally of the car at either end of the cross beams, is a plate member 7 which connects the ends of the beams and adds to the strength of the 10 frame. It is desirable to provide two of these cross beams located in the proper relation beneath each of the tanks, and consequently in a four tank car there are eight cross beams, and at either end of the car 15 there is a cross frame member 8 which completes the structure and to which the draw-bar connections are attached. The cross beams are placed symmetrically under the tanks so that the weight is distributed evenly. While the car frame construction just 20 described is that which is considered most desirable, it is clear that various other constructions may be employed, provided the frame has the necessary strength to carry 25 the weight of the tanks and is so arranged as to provide a convenient means of anchoring the tanks in place. Each tank as shown is of substantially cylindrical form, having a cylindrical body portion 9 with rounded 30 ends 10. The longitudinal axis of the tank lies substantially in the longitudinal axis of the car, and the tank is preferably made by welding so that it may be considered one continuous piece of metal. Each tank is of 35 a size sufficient to contain a considerable quantity of the liquid contents and as illustrated, the tank is intended to contain 7½ tons of liquid chlorine. Each tank is supported in place by means of a cradle which 40 is formed of four members. There is a transverse cradle member 11 riveted or otherwise secured on top of each cross beam. This cradle member has a central curved depression 12 which conforms substantially to 45 the contour of the cylindrical portion of the tank. The tank consequently rests with its cylindrical surface received in the curved portions of a pair of these transverse cradle members. At the end of the end tank there 50 is an additional cradle member 13, which is riveted or otherwise secured to the box girder. This cradle member has a curved portion 14 conforming generally to the curvature of the end of the tank, and between a 55 pair of tanks is a double cradle member 15, secured to the box girder and having curved portions 16 at either end which conforms to the curvature of the tank ends. The cradle member between each tank is, in general, 60 similar to that indicated at 13, but is arranged to cooperate with two of the tanks, one on either side of it. These transverse and longitudinal girder members may be of any desired construction, but are so formed 65 that when the tank is placed therein its

weight causes it to be anchored quite firmly in place and the cradle members have portions which extend up about the lowest point on the tank to provide stops against lateral and longitudinal movement of the tank. 70

The tank is further held in place in the cradle so formed, by means of girth straps 17 which encircle the tank and which are secured at their ends to any convenient part of the car frame. As shown, the transverse 75 cradle members 11 are somewhat U-shaped in cross section, and the ends of the straps extend through holes drilled in the flat upper edge of these cradle members and are held in place by means of nuts and lock 80 nuts 18. It is not essential that this arrangement should be followed, but it provides an advantageous means of anchoring the tank in position. It is intended that the tank shall form substantially a part of the 85 car and that the contents of the tank shall be placed therein and removed therefrom while the tank is on the car, but should it be necessary, for any reason, to remove the tank, as, for instance, for purposes of repairing, it will be seen that this operation is carried on without difficulty. Also, it will be noted that this tank is held firmly in position but without the use of any devices which extend through the shell of the tank. 90 Consequently any strains to which the tank and its mounting may be subjected during transportation can cause no leakage, since there are no bolts or rivets through the tank wall and there is no possibility of leakage due to the shearing or straining of a rivet or bolt. 95

At its upper end each tank is provided with a manhole 19, having the usual cover 20 in which may be mounted safety devices 105 such as are commonly employed. Extending through the cover plate are draw-off pipes 21 and 22. The pipe 21 extends downwardly into the tank and at its lower end enters a depression 23 formed in the lower cylindrical wall of the tank. The draw-off pipe 21 provides a means for removing the contents of the tank in liquid form, and the depression permits the contents of the tank to be entirely removed in the event that the 110 car is resting on a track which is slightly inclined. The draw-off pipe 22 extends only a short distance into the tank and is intended for the removal of the contents in gaseous form. Beyond the cover plate 20 these pipes are provided with the usual valves 24 and 25, and these valves are protected by means of a housing 26, having a cover 27 which may be easily removed when the valves are to be operated. Each valve has an outlet 115 pipe 28 extending through the wall of the housing, and as shown in Fig. 2 these outlet pipes are connected to mains 29 and 30 extending throughout the length of the group of tanks. Between each pair of tanks each 120 125 130

main has an expansion bend 31 for the usual purpose and the mains are provided at suitable points with couplings or other devices by which a connection may be made to the 5 container on the ground into which the contents are to be delivered.

In order to protect the tanks from damage which might result from sudden expansion of the contents, the tanks are enclosed in 10 insulation, indicated generally at 32. Any convenient form of insulating material may be used for this purpose, as, for instance, magnesia compounds. This insulating material is held in place in part by floor plates 15 33 which extend throughout the length of the series of tanks and provide a floor of sufficient width to support the necessary quantity of insulation to enclose the tanks. These floor plates may be of any light construction, having sufficient strength for the 20 purpose. The insulation is held in place and protected from the weather by means of a housing 34 which extends throughout the length of the tanks, and is made of light 25 metal construction. At its upper surface the housing is curved to conform to the upper surface of the tanks, and with this arrangement a body of insulation may be employed which extends down between the tanks and 30 beneath them, thus enclosing all portions of the tanks and protecting the contents most satisfactorily from temperature changes. Extending along this housing and secured in place thereon by suitable brackets 35, 35 are runways 36 which provide a convenient means to permit the workman to operate the tank valves. Extending down at about the central point of the car are ladders 37 by means of which the workman may reach 40 the runways 36. Also extending along the ends of the cross beams on either side of the tank are running boards 38 for the trainmen, and if desired hand rails may be secured to the outer surface of the housing 45 34 at a convenient height above these running boards, to insure the safety of the brakeman.

It will be seen that the multi-tank car of the present invention is of simple construction, but nevertheless of great strength and 50 the tanks are held securely in position and thus prevented from movement which might cause injury, which would, in turn, result in leakage. In each case the tank is held in 55 place on the car in such a way that there are no rivets or bolts which pass through the tank wall. Thus any strains to which the car is subjected cannot result in injury to the tanks by straining a rivet. The 60 securing means is wholly exterior to the tank and is so arranged that a tank may easily be removed should occasion arise, though it is to be understood, of course, that ordinarily the tanks will be kept in place and 65 the contents introduced and removed

through the draw-off connections. The car provides a means of transporting large quantities of liquefied material and the tonnage capacity of the car is used to the best advantage because the aggregate contents of 70 the car corresponds closely to the usual car load tonnage.

When the car has reached its destination the tanks may be quickly emptied, either singly or simultaneously, and the contents of each tank may be removed either in the gaseous or liquid form, as may be desired. Since the car permits of the transportation of so great a tonnage of material in one shipment, the costs of transportation 75 are materially reduced and it will be understood that in tank cars of this character it is most unusual for the car to be used for transportation during its return journey. There is consequently a loss in transportation, but in the present instance this loss is 80 kept to a minimum because of the greater quantity of material which can be handled in the outward journey. This tank car provides numerous advantages over those which 85 are in the form of a single tank, since there is but very little strain placed on each tank during transportation, owing to the shifting of the contents. Furthermore, with this type of tank it is possible to make use of 90 securing means as shown, none of which pass through the tank wall. These tanks also are so designed that they may be easily cleaned and kept in proper condition.

While the present car is illustrated as being built up of a frame made of a box girder and cross beams, various other frame constructions could be employed, provided the desired strength and rigidity were secured. Also, instead of using a floor which is somewhat closely limited to the area covered by the tanks, it is possible to extend this floor throughout the entire framework, in which case it would be unnecessary to provide the running boards 38. The present construction, however, is preferred by reason of the 95 less expense involved.

I claim:

1. In a car of the type described, the combination of a body comprising a central 100 girder and a plurality of cross beams, a plurality of cylindrical containers mounted on the body end to end in a single row with their long axes placed lengthwise of the body, a cradle member mounted over 105 each cross beam and extending across the central girder, each container resting on a pair of cradle members, and means for confining the containers in their cradles.

2. In a car of the type described, the combination of a body comprising a central longitudinal girder and a plurality of cross beams arranged in pairs, a plurality of cylindrical containers mounted on the body 110 end to end in a single row with their long 115 axes placed lengthwise of the body, a cradle member mounted over each cross beam and extending across the central girder, each container resting on a pair of cradle members, and means for confining the containers in their cradles.

axes lengthwise of the body, a cradle member mounted on and secured to each cross beam, each container resting on a pair of these cradle members and a cradle member secured to the central girder and engaging the heads of the containers for preventing their longitudinal displacement.

3. In a car of the type described, the combination of a body comprising a longitudinal girder and cross beams, arranged in pairs throughout its length, a plurality of cylindrical containers mounted on the body in a single row with their long axes parallel to the long axis of the body, each container being disposed over a pair of cross beams, a floor mounted on the body, a cradle member secured to each cross beam for supporting one end of a container in spaced relation to the floor, and cradle members secured to the longitudinal girder between the containers for preventing their longitudinal movement.

4. In a car of the type described, the combination of a body comprising a longitudinal girder and cross beams, arranged in pairs throughout its length, a plurality of cylindrical containers mounted on the body with their long axes parallel to the long axis of the body, each container being disposed over a pair of cross beams, a floor on the body, a cradle member secured to each cross beam for supporting one end of a container in spaced relation to the floor, cradle members secured to the longitudinal girder between the containers and serving to prevent their longitudinal movement, and a body of insulation encasing the containers, part of this insulation lying between the bottom surfaces of the containers and the floor.

5. In a car of the class described, the combination of a body, a plurality of cylindrical containers mounted thereon, draw-off connections for each container at the top thereof, and a main running lengthwise of the car body and connecting the draw-off connections.

6. In a car of the class described, the combination of a body, a plurality of cylindrical containers mounted thereon in a row, draw-off connections for each container disposed at the top thereof, a main connecting the draw-off connections of the several containers and a running board mounted on the containers and extending throughout the row.

7. In a car of the class described, the combination of a body comprising a central girder and a plurality of cross beams arranged in pairs, a floor on the body, a plurality of cylindrical containers mounted on the body in a single row with their long axes lengthwise of the body, cradle members on the body for securing the containers in place, the weight of each container being

taken by a pair of cross beams and the central girder, a body of insulation encasing each container, a housing on the top of each container extending through the body of insulation, and draw-off connections having outlets within the housing.

8. In a car of the class described, the combination of a body, a plurality of cylindrical containers mounted thereon end to end, with their long axes parallel to the long axis of the body, draw-off connections for each container located at the top thereof, and a running board mounted on the containers and extending throughout the series.

9. In a car of the class described, the combination of a body, a plurality of cylindrical containers mounted thereon end to end, with their long axes parallel to the long axis of the body, cradle members on the body for supporting each container in spaced relation to the body and for preventing lateral and longitudinal displacement of the containers, means for holding the containers in their cradles and insulation substantially enclosing the containers and their holding means.

10. In a car of the type described, the combination of a body comprising a central girder and cross beams, a cradle member mounted on and secured to each cross beam, a plurality of cylindrical containers supported on pairs of the cradle members end to end along the body with their long axes parallel to the long axis of the body, means for holding the containers in place and secured to the said cradle members, and a plurality of cradle members secured to the central girder between the containers and engaging the heads of the latter to prevent their longitudinal and lateral displacement.

11. In a car of the type described, the combination of a body comprising a central girder and cross beams, cylindrical containers mounted on the body end to end with their long axes parallel to the long axis of the body, a cradle member resting on and secured to each cross beam, and cradle members on the central girder at the ends of each container, each container being supported by a pair of each kind of cradle members.

12. In a car of the type described, the combination of a body, cylindrical containers mounted on the body end to end with their long axes parallel to the long axis of the body, cradle members on the body for receiving the containers and preventing their longitudinal and lateral displacement, means for confining the containers in the cradles, insulation completely encasing all of the containers, and a protective sheathing enclosing the insulation and all of the containers.

13. In a car of the type described, the

- combination of a body comprising a girder and cross beams arranged in pairs throughout its length, a plurality of cylindrical containers mounted on the body end to end with their long axes parallel to the axis of the body, each container being supported over a pair of cross beams, means on the body for supporting the containers thereon and for preventing their lateral and longitudinal displacement, means for securing each container in position on the supporting means, a body of insulation encasing all of the containers, and a protective sheathing for enclosing the body of insulation.
14. In a car of the type described, the combination of a body comprising a central girder and cross beams arranged in pairs along the latter, a plurality of cylindrical containers mounted end to end along the body, each container resting upon a pair of cross beams, cradle members mounted on the girder and cross beams for supporting the containers, these cradle members being so formed as to prevent the longitudinal and lateral displacement of the containers, draw-off connections on the top of each container, a body of insulation enclosing all of the containers, and a protective sheathing for the body of insulation enclosing all the containers while exposing the draw-off connections.

15. In a car of the type described, the

combination of a central girder extending longitudinally of the car, cross beams secured to the central girder and extending from one side to the other of the car, a cradle member resting on and secured to each cross beam and having a central depression to receive a cylindrical container lying longitudinally of the car body, and cradle members secured to the central girder between pairs of the cross beams and adapted to engage the heads of containers resting on a pair of the cradle members first mentioned.

16. In a car of the type described, the combination of a body comprising a central girder and a plurality of cross beams, a cradle member resting on and secured to each cross beam and also resting on the central girder, a plurality of cylindrical containers, each of which rests on a pair of the said cradle members, cradle members secured to the central girder at the ends of the containers and adapted to abut these ends to prevent longitudinal displacement of the containers, means secured to the cradle members first mentioned for holding the cradle members in position and insulation substantially enclosing the containers and the holding means.

In testimony whereof I affix my signature.

MAX MAURAN.
